ATTORNEY

UNITED STATES PATENT OFFICE.

ARTHUR L. BREITENSTEIN, OF AKRON, OHIO.

DESIGN FOR AN ELASTIC VEHICLE TIRE.

61,030.

Specification for Design.

Patented June 6, 1922.

Application filed December 20, 1919. Serial No. 346,395. Term of patent 3½ years.

To all whom it may concern:

Be it known that I, ARTHUR L. BREITENSTEIN, a citizen of the United States, residing at Akron, in the county of Summit and State of Ohio, have invented a new, original, and ornamental Design for Elastic Vehicle Tires, of which the following is a specification, reference being had to the accompanying drawing, forming a part thereof.

Figure 1 is a plan view of a portion of an elastic vehicle tire, showing my new design, and,

Figure 2 is a transverse sectional view of same, taken on line 2 of Figure 1.

I claim:

The ornamental design for an elastic vehicle tire as shown.

ARTHUR L. BREITENSTEIN.
